UNITED STATES PATENT OFFICE.

JOHN L. SHRODE, OF MOUNT VERNON, ILLINOIS.

AUTOMATIC EXPANSION VALVE.

Application filed February 21, 1924. Serial No. 694,354.

To all whom it may concern:

Be it known that JOHN L. SHRODE, a citizen of the United States, residing at Mount Vernon, in the county of Jefferson and State of Illinois, has invented certain new and useful Improvements in Automatic Expansion Valves, of which the following is a specification.

This invention relates to improvements in expansion valves such as are employed in refrigerating systems in effecting expansion of the liquid refrigerant, under high pressure, to gaseous form at a comparatively low pressure.

Such valves as ordinarily constructed present various disadvantages. In most types of such valves, the parts are so constructed and arranged that, due to expansion of the liquid refrigerant within the valve proper, the lubricant is congealed and when this occurs it is necessary to thoroughly clean the valve before the system can again be set in operation. Furthermore, in valves of this type, where the construction and arrangement of parts is such as to permit of expansion of the liquid refrigerant within the valve itself, the casing of the valve is cooled to such a low temperature that atmospheric moisture will be condensed and congealed upon the exterior surface of the valve casing, forming a frosty coating which causes a drip when the system is shut down, and the casing is brought to atmospheric temperature. Furthermore, valves of this type

where the construction and arrangement of parts is such as to permit of expansion of the liquid refrigerant within the valve itself, the high velocity of the gas at the point of expansion, scores and cuts the valve and seat, causing the valve to leak and prevents the compressor from maintaining the proper pressure in the low side of the system. Therefore, the present invention has as one of its most important objects to provide an

expansion valve so constructed that there will be no appreciable expansion of the liquid refrigerant in its passage through the valve so that none of the disadvantages outlined above will attend the operation of the valve, thereby avoiding the necessity of repeatedly cleaning the valve of congealed lubricant, obviating dripping of water from the exterior of the valve casing when the system has been shut down, and obviating freezing of moisture in the valve casing

above the diaphragm which would cause sticking of the valve.

Another object of the invention is to so construct the valve that expansion may be effected at any desired distance from the valve, thereby eliminating the cutting and scoring action to which the valve and its seat are ordinarily subjected.

Another important object of the invention is to provide a novel form of valve and novel form of valve seat, and a novel means for supporting the valve in operative relation to the seat such that the parts may function with the greatest efficiency and without liability of displacement or disarrangement of the parts.

In valves of this type it has heretofore been customary to manufacture them in different sizes depending upon the size or capacity of the refrigerating apparatus in connection with which the valves are to be employed. The expense of manufacturing different sizes of valves is considerable and the present invention therefore contemplates providing a valve so constructed that discharge tubes having bores of different diameters may be substituted one for another and in this manner I am enabled to employ a standard size of valve upon refrigerating apparatuses of varying capacities. In this connection the invention also contemplates so mounting the discharge tube that it will be air insulated, in one form of the invention, and, thereby prevent frosting of the valve body.

Another object of the invention is to provide a valve and valve seat which will not corrode or be in any way affected by the high velocity of the gas at the point of passage past the said valve and seat.

In the accompanying drawing, the figure is a diametric sectional view illustrating the construction of the improved valve.

Referring to the accompanying drawing, the valve casing is indicated in general by the numeral 1 and the same comprises a body 2 which is of substantially solid structure. That is to say, the body is not of hollow construction but the necessary passages or ducts formed therein are of minimum size so that expansion within the valve casing will be reduced to the minimum or entirely eliminated. The upper side of the body 2 of the casing is provided with a flat smooth surface 3 upon which is disposed an annular

packing ring or gasket 4 which supports the peripheral portion of a diaphragm 5. The numeral 6 indicates in general a bonnet which is removably secured by bolts or other suitable fastening elements 7, upon the upper side of the body 2 of the valve casing, and between the under face of which bonnet and the upper face 3 of the said body 2, the gasket 4 and the peripheral portion of the diaphragm are securely clamped. In its flat upper face 3 the valve body 2 is provided with a shallow chamber 8 which is within the bounds of the packing ring 4 and over which the diaphragm 5 extends. The under side of the bonnet 6 is likewise provided with a shallow chamber 9 which is located above the diaphragm. The dome of the bonnet 6 is formed in its top with a threaded opening 10 into which is adjustably threaded an adjusting screw 11 formed at its upper end, as at 12, for the application of a wrench or other tool whereby it may be rotated, a lock nut 13 being fitted onto the said screw and being adapted to be adjusted to bear against the upper side of the top of the dome. The lower end of the screw 11 is preferably rounded and seats in a recess 14 formed in the upper side of a bearing disc 15 which rests at its peripheral portion upon the upper end of a compression spring 16 arranged within the said dome. The lower end of the spring 16 rests upon a bearing disc 17 which has a convex under side 18 resting at its central portion upon the upper side of the diaphragm 5. The valve casing body 2 is formed with an inlet duct indicated by the numeral 19, the discharge end of which duct, indicated by the numeral 20, communicates with a chamber 21 formed in the lower side of the said casing body 2 in axial alignment with the bonnet 6. The numeral 22 indicates a cap member which is disposed against the under side of the casing body 2 and is secured thereto in position closing the chamber 21, by means of bolts or other fastening elements 23, a packing ring or gasket 24 being interposed between the upper side of the cap member at the peripheral portion thereof and the under side of the casing body 2. The cap member 22 is preferably provided centrally in its upper side with a chamber 25, and, surrounding this chamber, with an upstanding annular flange 26 which seats within the chamber 21. Housed within the chamber 25 is a compression spring 27 which at its lower end seats in a shallow seat 28 in the bottom of the chamber 25, and at its upper end bears against the under side of a valve carrier which is indicated by the numeral 29. The valve proper is indicated in general by the numeral 30 and the same comprises a cylindrical stem 31 fitting snugly in an opening 32 formed centrally in the valve carrier 29, the head of the valve being

indicated by the numeral 33 and being of frusto-conical form. The valve in its entirety is preferably formed of the alloy known commercially as "stellite". This alloy is exceedingly hard and, in fact, so hard that it cannot be machined, and likewise it is non-corrosive. The seat for the valve, which is indicated by the numeral 34, is formed of the same material and is in the nature of a flat annular disc having a central opening which is of conical form to accommodate the head of the valve.

The body of the valve casing is formed with a vertically extending axial bore 36 into the lower end of which there is threaded a nipple 37 having an axial bore 38 in alignment with the axis of the bore 36, the lower end of the bore 38 being enlarged to receive the valve seat 34 which is shrunk in place. Arranged within the bore 36 is a stem 40, the upper end of which stem projects into the chamber 8 and engages the under side of the diaphragm 5 at a point corresponding to the point of engagement of the convex under side 18 of the bearing disc 17 with the upper side of the said diaphragm. At a point between its ends, the stem 40 is reduced in diameter, as indicated by the numeral 41, and below this portion and throughout the remainder of its length, the stem is further reduced in diameter as indicated by the numeral 42, this last-mentioned reduced portion of the stem fitting loosely through the bore 38 of the nipple 37. The stem 40 has a smooth fit within the bore 36 and is flat on one side so that the refrigerant entering through the intake passage 19, may flow past the valve 30 and seat 34 and through the bore 38 and the bore 36 and into the chamber 8 and, under certain conditions, exert pressure against the under side of the diaphragm 5.

Formed in the casing body 2 and communicating at end with the bore 36 at a point substantially opposite the reduced portion 41 of the stem 40, is an outlet bore 43 which is enlarged at its opposite end, as at 44, and interiorly threaded, the bore being further enlarged, as at 45, and the enlargement 45 being of considerable diameter in comparison to the diameter of the bore 43 and extending from the threaded enlargement 44 to the exterior of the valve casing where it opens to the atmosphere. The discharge tube of the valve is indicated by the numeral 46 and at one end is threaded, as indicated by the numeral 47 thus adapting this end to be removably fitted into the threaded enlargement 44 of the bore 43. The bore of the discharge tube 46 is indicated by the numeral 48 and in practice a number of the tubes will be manufactured having bores of different diameters, it being contemplated that a tube having a bore of a required diameter be threaded into the

enlargement 44 of the bore 43 in accordance with the capacity of the refrigerating apparatus, it being possible therefore to substitute one tube for another in a standard size of valve in accordance with the varying capacities of different refrigerating apparatuses. It will be observed that the external diameter of the discharge tube 46 is less than the diameter of the enlargement 45 of the bore 43, so that an air space 49 is provided surrounding the said tube 46, the air within the space constituting an insulating medium so as to prevent frosting of the casing 2 which would otherwise occur, due to conduction, if the valve casing should be formed merely with a bore extending from and communicating with the bore 36 and to the atmosphere.

The valve is automatic in its operation. In adjusting the valve to permit flow of the liquid refrigerant through the valve to the discharge tube 46, and thence to the point where the refrigerant is permitted to expand, the screw 11 is adjusted so as to suitably tension the spring 16 and cause the same to exert pressure upon the diaphragm 5, and stem 40, to move the conical head 33 of the valve 30 away from the seat 34. The liquid refrigerant will then flow from the intake bore 19 into the chamber 21 and past the valve head 33 and its seat 34, and through the bore 36, the bore 43, and the bore 48 of the discharge tube 46. The refrigerant will also exert pressure, within the chamber 8, against the under side of the diaphragm 5 and when the pressure against the underside of the diaphragm becomes greater than that exerted by the spring 16, the spring 27 will act to move the valve carrier 29 upwardly so as to cause the head 33 of the valve 30 to rest in its seat 34 thus cutting off the supply of refrigerant until such time as the suction of the pump of the refrigerating system has reduced the pressure on the lower face of the diaphragm 5 to a degree less than that exerted by the spring 16, whereupon the said spring will act to again open the valve and permit the refrigerant to flow as before. This auto-

matic operation of the valve will continue so long as the system is in operation and it will be evident from the foregoing and by reference to the drawings that there is no appreciable expansion of the liquid refrigerant within the valve and that expansion is permitted only at a point more or less removed from the valve.

Having thus described the invention, what is claimed as new is:

1. An expansion valve of the class described comprising a casing having an inlet passage and an outlet passage, and a valve within said casing to control passage of fluid through the casing from the inlet passage to the outlet passage, said outlet passage having its intermediate portion threaded, its inner end portion of materially less diameter than the threaded intermediate portion and from the said intermediate portion to its outer end of materially increased diameter, said intermediate portion constituting a socket whereby discharge tubes of a common external diameter and of varying internal diameters may be selectively passed through the enlarged outer portion of said outlet passage in spaced relation to the walls thereof and screwed into said socket.

2. An expansion valve of the class described comprising a casing having an inlet passage and an outlet passage, and a valve within said casing to control passage of fluid through the casing from the inlet passage to the outlet passage, said outlet passage having its intermediate portion of materially greater diameter than its inner end portion and of materially less diameter than the portion of the outlet between its outer end and intermediate portion, said intermediate portion of the outlet constituting a socket, and discharge tubes extending axially through the enlarged outer portion of said outlet in spaced relation to the walls thereof and having its inner end portion removably secured in said socket.

In testimony whereof I affix my signature.

JOHN L. SHRODE. [L. S.]
